Attorney

UNITED STATES PATENT OFFICE.

JESSE L. RENEAU, OF PARIS, TEXAS.

COMBINATION SELF-LUBRICATING AND GERMICIDAL RAZOR HONE.

Application filed March 13, 1922. Serial No. 543,306.

To all whom it may concern:

Be it known that I, JESSE LEE RENEAU, a citizen of the United States, residing at Paris, in the county of Lamar and State 5 of Texas, have invented certain new and useful Improvements in Combination Self-Lubricating and Germicidal Razor Hones, of which the following is a specification, reference being had to the accompanying 10 drawing.

Heretofore hones have been used where the lubricant is applied to the exterior of the hone, for the purpose of sharpening the razor, and as the germicidal lubricant is 15 absorbed, it necessitates further supply, to keep the hone in condition, whereby the razor may be properly honed.

Therefore, it is the purpose of the present invention to entirely avoid this method, 20 by providing a combination self-lubricating and germicidal hone, wherein the germicidal lubricant is permitted to percolate or feed through the pores of the hone to the surface thereof, to insure a constant supply, 25 as the razor is honed.

In order to accomplish this result it is the aim to provide a hone comprising two 30 sections with cavities in the adjacent faces of the sections, to receive a germicidal lubricant, so that such substance may percolate or feed through the pores of the hone to the surface thereof, for honing the razor blade, and when accomplishing this result, 35 to enable it to be done in a sanitary manner.

Another purpose is to provide a pair of hone sections, with cavities in the adjacent faces thereof, in combination with recesses 40 at the ends of said sections, so that when the sections are placed together, the recesses will register, and thereby provide a filling opening, through which the germicidal lubricant may be poured, for the purpose of filling the cavities, there being a suitable band surrounding the adjacent portion 45 of the two sections of the hone, to assist in holding the two sections together, and avoiding leakage of the material therein.

Still another purpose is the provision of 50 a hone constructed of any suitable blade sharpening honing composition, and of such a character as to permit the razor blade to be easily and very quickly sharpened, such material being of a character to permit the germicidal lubricant to perco-

late through the pores of the material, for 55 the purpose of reaching the surface thereof, and enable the razor blade to be thoroughly sharpened and sterilized.

A further purpose is to provide a hone which will produce a perfect shaving razor 60 edge, without the use of a strop, and furthermore it is the aim to provide a hone consisting of two sections, one section to be used to produce the teeth or edge (as 65 termed by barbers), and the other section, by which a perfect shaving razor edge may be produced thereby doing away with stropping altogether. In this way a combination self-lubricating and germicidal razor 70 hone is devised.

It is to be understood that the particulars herein given are in no way limitative and that while still keeping within the scope of the invention, any desired modifications of detail and desired proportions may be 75 made in the apparatus according to circumstances.

The invention comprises further features and combination of parts, as will be herein-after set forth, shown in the drawings and 80 claimed.

In the drawings:—

Figure 1 is a view in perspective of the improved combination self-lubricating and germicidal razor hone constructed in accordance with the invention; 85

Figure 2 is a longitudinal sectional view on line 2—2 of Figure 1;

Figure 3 is a cross sectional view on line 3—3 of Figure 2; and 90

Figure 4 is a detail perspective view of one of the sections of the hone.

Referring to the drawings, 1 and 2 designate the two plate-like sections of the hone, which may be any suitable shape or configuration, preferably rectangular, and which may be any suitable thickness. Each section of the hone is designed to be constructed of a suitable honing composition, of a porous nature, so that when the razor is given a requisite number of strokes on the red section, a toothed edge may be given to the razor, and then when the hone is reversed, and a requisite number of strokes is given the razor on the blue section, a perfect shaving razor edge may be produced, thereby removing the nicks in the teeth, and producing an even edge. In other words 100

95

100

105

110

the blue section of the hone is used for producing a finished edge on the razor, far better than can be produced by using the old form of hone and a strop. The two sections are differently colored, in order to render it indicative as to the section for producing the toothed edge, and the section to produce the even or finished edge.

Each section is provided with an elongated rectangular depression 3, and therefore when the two sections are placed together in register, a suitable cavity 4 is caused to be formed, for the reception of the germicidal lubricant. The germicidal lubricant is permitted to percolate through the pores of the material of which the hone sections are constructed, in order to enable the material to reach the surface thereof, for the purpose of honing the razor.

The corresponding ends of the adjacent faces of both sections of the hone are provided with recesses 5, which, when the two sections are disposed in register, form a filling opening 6, through which the germicidal lubricant may be poured, for the purpose of filling the rectangular interior of the hone with said lubricant. It is obvious that this germicidal lubricant percolates through the pores of the sections of the hone, for the purpose of reaching the surface thereof for sterilizing, insuring a proper razor edge, and also to lubricate the blade and prevent corrosion.

It will be noted that the two sections on their sides and ends, adjacent their engaging surfaces, are rabbeted as shown at *a* and *b*, for the reception of the metal band, serving to cover the adjacent meeting surfaces of the two sections. In this way the band is countersunk in the sections, so that its outer face is flush with the sides and ends of the hone. The band is not only used for holding the two sections 1 and 2 in register, but is also used to give the hone a nice finished appearance. In fact the band may be highly nickel-plated or otherwise finished, and may contain on its outer face an inscription, or advertisement, or the name of the owner, which may be cut or engraved or otherwise applied to the band. The adjacent faces of the two sections may be articulated, or joined together by a non-porous cement or glue material to prevent leakage from between the sections.

The filling opening 6 receives a suitable cork 6^a, for closing the opening and retaining the germicidal lubricant within the hollow 4 of the hone. The band 7 where it overlies the opening 6 is provided with a threaded opening registering with the opening 6, and receives a threaded screw plug 7^a, which covers the cork or plug 6^a. When it is desired to refill the hone, a suitable screw driver may be inserted in the kerf of the screw plug and

the plug easily removed. After the screw plug 7^a is removed, the cork 6^a may be withdrawn, and the germicidal lubricant poured into the cavity of the hone.

The lubricant used within the hone will become impregnated with a germicide, so that whenever a razor is being honed or comes in contact with the hone, it will be thoroughly sterilized, which is one of the most important features of the invention, particularly due to the fact that it obviates the necessity of subsequently sterilizing the blade.

As stated before the hone is constructed of any suitable honing composition, of a porous nature, such as any suitable emery, slate, carborundum, petrified hickory, or any razor hone sharpening material, or may be made of a combination of two or more of such or other well known razor sharpening materials. It is obvious the material, or a combination of the aforesaid substances may be of different proportions in the combined aggregation of the material and the germicidal lubricant used in the hone, in order to cause the same to give the desired results, both as to producing and finishing up a perfect shaving edge, and for sterilizing the razor to prevent infection after shaving, and also to prevent corrosion on the razor. In other words, the lubricant used not only cooperates with the hone to produce a proper shaving edge, but is also an antiseptic, acting materially in protecting the customer or other person being shaved, from any possible infection from the razor.

The invention having been set forth, what is claimed is:—

1. A hone comprising two plate-like honing stones of different texture and of a porous nature, secured together back to back to form a compound hone, said stones being provided with complemental recesses in the backs thereof providing a liquid chamber, and being further provided with a filling opening communicating with said chamber and provided with a removable closure.

2. A hone comprising two plate-like honing stones of different texture and of a porous nature, secured together back to back to form a compound hone, said stones being provided with complemental recesses in the backs thereof providing a liquid chamber, and being further provided with a filling opening communicating with said chamber and provided with a removable closure, said stones having mating recesses forming said filling opening.

3. A hone comprising two plate-like honing stones of different texture and of a porous nature, secured together back to back to form a compound hone, said stones being provided with complemental recesses in the backs thereof providing a liquid chamber,

and being further provided with a filling opening communicating with said chamber, said stones having mating recesses forming said filling opening, a band counter-sunk 5 in the outer surface of and extending around said hone and overlying the joint between the stones, said band having a screw

threaded opening aligned with the filling opening, a stopper in said filling opening, and a plug threaded in the opening of the 10 band for retaining the stopper in place.

In testimony whereof I hereunto affix my signature.

JESSE L. RENEAU.
